UNITED STATES PATENT OFFICE.

GEORGE A. SCHULTZE, OF PATERSON, NEW JERSEY, ASSIGNOR TO DEPOSIT CHECK COMPANY, OF NEWARK, NEW JERSEY, A CORPORATION OF NEW JERSEY.

DESIGN FOR A TOKEN.

48,952.

Specification for Design.

Patented Apr. 25, 1916.

Application filed January 15, 1916. Serial No. 72,355. Term of patent 14 years.

To all whom it may concern:

Be it known that I, GEORGE A. SCHULTZE, a citizen of the United States, residing in Paterson, Passaic county, and State of New Jersey, have invented a new, original, and ornamental Design for a Token, of which the following is a specification, reference being had to the accompanying drawing, forming a part thereof.

In the drawing, illustrating my new design Figure 1 shows one face of the token; and, Fig. 2 shows the edge thereof.

I claim:

The ornamental design for a token, substantially as herein shown.

GEORGE A. SCHULTZE.
